UNITED STATES PATENT OFFICE.

AUGUST HANKE, OF CHICAGO, ILLINOIS.

DESIGN FOR A LEMON-SQUEEZER HANDLE.

SPECIFICATION forming part of Design No. 23,403, dated June 26, 1894.

Application filed November 8, 1893. Serial No. 490,395. Term of patent 7 years.

To all whom it may concern:

Be it known that I, AUGUST HANKE, a citizen of the United States, residing at Chicago, in the county of Cook and State of Illinois, have invented certain new and useful Improvements in a Design for a Lemon-Squeezer Handle; and I do hereby declare the following to be a full, clear, and exact description of the invention.

The design consists in the new and useful shape and configuration of the handle of a lemon squeezer as hereinafter set forth and shown in the accompanying drawings.

In the accompanying drawings, Figure 1 represents a perspective view of the handle of a lemon squeezer made in accordance with my design. Fig. 2 is a longitudinal section.

The said drawings show a representation of a design for the handle of a lemon squeezer. The said handle is represented as consisting

of a part 1, that is represented as a compound curve with a decided downward curve at its inner end, where it joins a circular inverted cup-shaped part 2 at one side of the latter. At the other side of this circular, inverted cup-shaped part 2, is represented a part 3, rising therefrom and having an upward and downward curve. The configuration is novel, effective, agreeable and pleasing to the eye. 25

I claim as my invention—

The design for the handle of a lemon squeezer, substantially as shown and described.

In testimony whereof I affix my signature in presence of two witnesses.

AUGUST HANKE.

Witnesses:

HARRY COBB KENNEDY,
RUDOLPH W. LOTZ.
